UNITED STATES PATENT OFFICE.

JOHN H. STULL, OF OKOBOJO, DAKOTA TERRITORY.

RAILWAY-TIE.

SPECIFICATION forming part of Letters Patent No. 372,879, dated November 8, 1887.

Application filed July 9, 1887. Serial No. 243,847. (No model.)

To all whom it may concern:

Be it known that I, JOHN H. STULL, of Oko-
bojo, in the county of Sully and Territory of
Dakota, have invented a new and Improved
5 Railway-Tie, of which the following is a full,
clear, and exact description.

This invention relates to railway-ties, the
object of the invention being to provide a tie
wherein the several parts shall be connected
10 without the use of bolts or rivets and to which
the rails may be connected by means of keys,
all as will be hereinafter more fully described,
and specifically pointed out in the claims.

Figure 1 is a plan view of my improved form
15 of tie, a rail being shown in connection there-
with upon the right-hand side, said rail being
represented in section—that is, taken upon a
line drawn through the web of the rail. The
position of the rail is indicated upon the left-
20 hand side of the figure, but the fastening-keys
are removed. Fig. 2 is a plan view of the tie
with the chairs or plates removed. Fig. 3 is
a sectional elevation taken on line *xx* of Fig. 2.
Fig. 4 is a longitudinal sectional view taken
25 on line *yy* of Fig. 1, the rails, however, being
represented as in position at both ends of the
tie; and Fig. 5 is a cross-sectional view taken
on line *zz* of Fig. 1.

The tie proper consists of a sheet or plate of
30 metal, 10, that is cut and bent to form ears 11
at each end, the main body of the plate or
sheet of metal being bent to semicircular form,
or to such other form as is proper and may be
desired, the only requirement being that the
35 edges of the ears 11 shall closely approach, as
represented in Fig. 2. The ears 11 are each
formed with apertures 2 and 3, the apertures
2 being entered by lugs or ears 4, that are formed
upon chairs or plates 12, said chairs or plates
40 being provided with other upwardly and out-
wardly extending lugs or ears 5, beneath which
the bases of the rails are passed. The plates
12 are formed with apertures 6, which, when

the plates are adjusted to position, register
with the apertures 3 of the ears 11. These 45
apertures 3 and 6 extend in a direction trans-
verse to that of the length of the tie.

In order that the rails may be securely fast-
ened to the ties, I provide keys 15, which are
made up of lower claws, 7, and upper claws, 8, 50
a shank, 9, extending outward from these claws;
and in applying the keys the claw 7 is passed
down through the registering apertures 3 and
6, the shank 9 at this time being held in a po-
sition parallel with that of the rail; but after 55
the claw 7 has been passed through the aper-
tures 3 and 6 the shank is turned outward, so
as to extend at right angles to the rail, thus
bringing the claw 7 beneath its ear 11 and
bringing the claw 8 above the base of the rail, 60
the end of the shank being finally bent down-
ward beneath the ears 11, as is clearly shown
in Fig. 4.

Having thus fully described my invention, I
claim as new and desire to secure by Letters 65
Patent—

1. The combination, with a metallic plate-
tie provided with ears 11, of chairs or plates
connected to the ears and formed with up-
wardly-extending lugs, and keys adapted to 70
pass through the chairs and the ears, substan-
tially as described.

2. The combination, with a plate-tie, 10,
having ears 11, in which there are formed ap-
ertures 2 and 3, of plates or chairs 12, having 75
downwardly-extending lugs 4, that are ar-
ranged to enter the apertures 2, and upwardly
and outwardly extending lugs 5, apertures 6
being formed in the plates in positions to reg-
ister with the apertures 3, and keys 15, formed 80
with claws 7 and 8 and shanks 9, substantially
as described.

JOHN H. STULL.
